REFRIGERATING TRUNK FOR
AUTOMOBILES

Urbain Gelinas, Montreal, Quebec, Canada

Application August 26, 1929, Serial No. 388,597,
and in Canada August 7, 1929

4 Claims. (Cl. 190—12)

The present invention pertains to a novel device in the form of a valise or trunk adapted to be carried on the rear end of a motor vehicle and constructed to contain ice and food, as well as 5 clothing or other articles, in a convenient manner.

With this object in view, the device is built of insulating double walls with a hinged top and side and provided with a partition defining refrigerating and storage compartments. Both compartments may contain food, and an opening is formed in the partition to permit the passage of cool air from the ice compartment to the other. The storage compartment, on the 15 other hand is designed also to contain clothing, in which case the aforementioned opening is unnecessary and may be closed.

The hinged top and side make the interior of the device readily accessible, and the hinged side may in fact be supported in a vertical position to serve as a table.

The invention is fully disclosed by way of example in the following description and in the accompanying drawing in which

25 Figure 1 is a perspective view of the device in open condition;

Figure 2 is a perspective view of the device closed;

Figure 3 is a transverse vertical section;

30 Figure 4 is a perspective view of the ice tray;

Figure 5 is a detail view of the drain;

Figure 6 is a detail section showing the ventilation port; and

Figure 7 is a detail section of the drain.

35 Reference to these views will now be made by use of like characters which are employed to designate corresponding parts throughout.

In Figures 1 and 2 is shown a valise or trunk comprising a box-like body structure 1 having a top 2 hinged thereon as at 3 and adapted to be carried at the rear end of an automobile. The front wall 4 is also hingedly mounted at 5 and may be supported in a horizontal position by a chain 6 to serve as a table as shown in Figure 1. 45 A chain 7 attached to the top 2 prevents the latter from being opened too high. The sides of the device are each constructed of two spaced sheets 8 of insulating material with a dead air space 9 therebetween as illustrated in Figure 3.

50 The interior of the box is divided transversely by a fixed partition 10 forming an ice compartment 11 and a storage compartment 12. In the compartment 11 is supported a shelf 13 preferably consisting of screen or grating. In the front of the compartment 11 is slidably mounted a door

14 in guides 15 formed on the partition 10 and adjacent end wall of the box. The door is of sufficient height to cover the forward end of the space beneath the shelf 13 or to be raised to a higher position.

60 A tray 16 is adapted to rest on the shelf 13 and has a continuous flange 17 along three edges thereof and a depending flange 18 at the remaining edge. The tray is mounted on the shelf with the flange 18 at the rear of the compartment, as shown in Figure 3, for the purpose of supporting a cake of ice. The food is placed on the bottom of the box beneath the shelf, and the flange 18 conducts the water from the ice directly to the bottom of the compartment without interfering with the food. Water is drained from the bottom through a drain hole 19.

65 When the food contents are bottled or otherwise unaffected by water, the ice may be placed directly upon the screen shelf 13. In this case, the tray 16 may be placed in the bottom of the compartment 11, with its flange 18 extending upwardly. The water then drips upon the food to cool the same and flows down the flange 18 to the drain hole. In either case the door 14 is 70 closed to seal the food space beneath the shelf.

75 In the compartment 12, a screen or grating 20 is supported adjacent the partition 10 for a purpose which will presently appear. The member 20 in conjunction with the opposite end wall 80 of the compartment 12 supports a set of horizontal reticulated shelves 21 in any conventional manner.

85 The partition 10 has a small opening 22 cut therethrough but adapted to be closed by a sliding shutter 23 as shown in Figure 3. Thus, by opening the shutter, the cold air developed in the ice compartment may be caused to circulate through the compartment 12 when food is placed on the shelves 21. On the other hand, clothing may be packed into the compartment 12, and in this case the shutter 23 is closed to seal off the cold damp air developed in the ice compartment. It may now be pointed out that the grating 20 serves as a guard for preventing 95 objects in compartment 12 from contacting the partition 10 and becoming wet from the moisture condensed on the cold partition.

100 A ventilating hole 24 is cut through the exterior end wall of the compartment 12 and is fitted with a screen 25 to prevent entrance of dust. The bottom edge of the partition 10 has small holes 26 whereby moisture condensing on the side thereof in compartment 12 and flowing 105

110

downwardly may continue to flow into compartment 11 and to the drain hole 19.

5 Into the hole 19 is fitted a cone 27 having upright strips 28 with outward flanges 29 for supporting purposes, as shown in Figures 5 and 7. At the base of the cone are cut notches 30 which permit the escape of drain water but prevent the entrance of dust and air. The box or body may be tightly closed by means of a lock 10 31, latches 32 and straps 33. The body has handles 34 for lifting.

15 Although a specific embodiment of the invention has been illustrated and described, it will be understood that various alterations in the details of construction may be made without departing from the scope of the invention as indicated by the appended claims.

What I claim is:—

20 1. A device of the character described comprising a box-like body, a partition dividing the same into two compartments, means for accommodating ice and food in one of said compartments, and a grating at the side of said partition presented to the other compartment.

25 2. A device of the character described com-

prising a box-like body, a partition dividing the same into two compartments, means for accommodating ice and food in one of said compartments, and a grating at the side of said partition presented to the other compartment, said partition having an opening therethrough, and a shutter adapted to close said opening.

80 3. A device of the character described comprising a box-like body, a partition dividing the same into two compartments, means for accommodating ice and food in one of said compartments, and a grating at the side of said partition presented to the other compartment, and shelves in said other compartment.

85 4. A device of the character described comprising a box-like body, a partition dividing the same into two compartments, means for accommodating ice and food in one of said compartments, and a grating at the side of said partition presented to the other compartment, said partition having an opening therethrough, a shutter adapted to close said opening, and shelves in said other compartment.
